UNITED STATES PATENT OFFICE.

OLIVER C. RITZ WOLLER, OF CHICAGO, ILLINOIS.

DESIGN FOR AN ORNAMENT FOR AUTOMOBILE RADIATOR CAP OR SIMILAR ARTICLE.

Application filed December 15, 1927. Serial No. 24,499. Term of patent 14 years.

To all whom it may concern:

Be it known that I, OLIVER C. RITZ WOLLER, a citizen of the United States, residing at Chicago, in the county of Cook and State of Illinois, have invented a new, original, and ornamental Design for Ornament for Automobile Radiator Cap or Similar Article, of which the following is a specification, reference being had to the accompanying drawing, forming part thereof.

In the drawing—

Fig. 1 is a side elevational view and Fig. 2 is a perspective view of an ornament for automobile radiator cap or similar article showing my new design.

I claim:—

The ornamental design for an ornament for automobile radiator cap or similar article, substantially as shown.

OLIVER C. RITZ WOLLER.
